MILK DELIVERY BOX

John A. Hopwood, Great Neck, N. Y.

Application January 5, 1935, Serial No. 507

14 Claims. (Cl. 217—20)

This invention relates to delivery boxes and more particularly those used by retail milk dealers in the delivery of bottled milk to the ultimate consumer.

5 Boxes of the character referred to are generally constructed from wood and are of the slat type. They are provided internally with partition wires which divide the interior of the box into a plurality of compartments in which the 10 bottles are individually received, said bottles being supported upon so called supporting wires which extend across the box near the bottom thereof and on which the bottles rest. These supporting wires, while relatively heavy and in the form of 15 metal rods, require re-enforcement intermediate their ends, and this is generally provided for by means of one or more transverse braces through which the supporting wires extend in order to permit them to better carry the weight of the 20 bottles without sagging.

One object of the present invention is to provide a novel and efficient form of brace for the 25 said supporting wires and to so constitute said brace that it will simultaneously serve the function of a lower partition wire, whereby the necessity of a separate partition wire in juxtaposition with the brace is rendered unnecessary. In the event that a plurality of such braces are used, a corresponding number of lower partition wires 30 are dispensed with, so that in a twelve compartment box, the use of three supporting braces obviates the necessity of using any transverse lower partition wires. The resulting structure is 35 unusually strong and at the same time is highly economical because the necessity of lower partition wires is eliminated.

It has heretofore been proposed to utilize transverse braces for the supporting wires by making such braces in the form of hangers suspended 40 upon the lower partition wires, but such an arrangement necessitates a lower partition wire for each hanger and consequently doubles up on the parts, and adds to the expense and weight of the box.

45 One object of the present invention, as stated, is to so constitute the transverse braces that each serves the dual function of a brace and partition wire, in the interest of lightness and economy and without sacrificing strength.

50 Another feature of the present invention has to do primarily with the lower edge and corner construction of the box. Boxes of the kind herein under consideration are subjected to rough usage. They are thrown about carelessly by 55 drivers during the delivery of milk and at cream-

eries and depots, are handled on mechanical conveyors, slid along floors and roughly thrown into the wagons, trucks and cars. This sort of treatment is very apt to damage the lower edges of wooden boxes and produce splinters which interfere with their convenient handling. Accordingly, many retailers of milk require that the boxes which they use be provided with armored lower edges, i. e., edges which are covered or sheathed with metal in such a way as to adequately protect 10 them in use. It is essential, however, that these lower edges be substantially flush throughout, otherwise they are apt to catch on floors or mechanical conveyors.

With these considerations in mind, another 15 object of the present invention is to provide an improved armor and shielding for the box and to so associate with this shielding a novel corner construction that the box is effectually protected and shielded, not only at its lower edges, but at 20 its corners in a way to fully protect the box against wear and hard usage and to render the same strong and rigid.

The details of this edge armoring and corner construction will be hereinafter more fully described, but suffice it here to say that, in the preferred practical embodiment of this invention, the box is provided at its four corners with corner angles which enclose and conceal the joints between the slats of the sides and ends of the box 25 and, at its lower edges, is provided with substantially U-shaped strips which enclose the lower edges of the bottom slats, as well as the lower termini of the corner angles, and interlock with one another at the four corners of the box to 30 provide a strong flush construction.

Features of the invention, other than those 35 adverted to, will be apparent from the herein-after detailed description and claims, when read in conjunction with the accompanying drawings.

The accompanying drawings illustrate one 40 practical embodiment of the invention, but the construction therein shown is to be understood as illustrative, only, and not as defining the limits of the invention.

Figure 1 is a perspective view of a box embodying the present invention, with a portion of one side and one end wall of the box and certain partition wires broken away in the interest of clearness.

Figure 2 is a fragmental transverse section 45 through the box shown in Figure 1.

Figure 3 is a perspective view showing the box upside down to better show the bottom construction thereof.

Figure 4 is a fragmental view of one lower corner portion of the box with all reinforcement omitted.

Figure 5 is a similar view showing the corner angle in place.

Figure 6 is a detail of the corner angle detached.

Figure 7 is a detail perspective of the armor construction adapted to be associated with the lower edge of the box.

Figure 8 is a view similar to Figures 4 and 5, but showing the armor strips associated with the box.

Figure 9 is a section on the line 9—9 of Figure 8.

The box of this invention may be a slat box or it may have solid side and end walls, but, for the purpose of illustration, I have shown this invention as incorporated in a slat box construction. Thus the box is shown as having side walls composed of slats 1 and end walls composed of slats 2. The corresponding slats of the side and end walls constitute rectangular frames which are superimposed upon one another to form the body of the box and are adapted to be held in assembled relation by means of corner angles 3 and tie rods 4. One of the corner angles is shown in detail in Figure 6. It is made of sheet metal, the major portion of the length of which is bent at a right angle to cover and conceal the joints between the slats of the sides and ends of the box. The opposite ends of the sheet metal strip from which the corner angle is formed are slit along the longitudinal medial line of the strip 35 to form tongues 5 which are bent in overlapping relation to one another, as shown in Figure 6, and these tongues are adapted to overlie the upper and lower edges of the box, so that the tie rods 4 may be passed through perforations 6 in the tongues and through the several superimposed slats 1 or 2 in succession and also through the armoring strips, presently described, and headed over to secure the parts together.

At the lower edges of the box and at all of 45 the four corners, the bottom slats in proximity to the corners are cut out or recessed, as shown at 7, so that the tongues 5 may be received in these recesses to such extent that the outer surfaces of the tongues, as well as the wooden bottom edges of the box will be substantially flush 50 with one another. Over these bottom edges and over said tongues is next received strips 8 shown in detail in Figure 7. These strips are substantially U-shaped in cross section. They have flat bottoms 9 with upstanding flanges 10 at their 55 lateral edges. It should be noted that in Figure 7 they are shown as upside down to correspond with Figures 3-9, but in practice the strips 8 are placed primarily on the bottom edge of the box, so that the flanges 10 would normally extend in an upward direction. The strips 8 preferably 60 have an overall width substantially equal to the thickness of the bottom slats of the box and the lower margins of said slats are rabbeted, as shown at 11, so that when the strips are in place on the box, the walls of such box will be flush inside and out. In other words, the strips 8 preferably 65 do not project beyond the faces of the walls of the box, although they may do so without departing from this invention in which event the rabbets 11 may be omitted.

The strips 8 are made of a length to entirely 70 cover the lower edges of the lowermost slats and they are mitered at the corners of the box to abut one another. Nevertheless in the formation of

such miters, they are provided with projecting wings 12 offset in an upward direction as shown at 13, and so proportioned that when the miters are brought together, the wing 12 of one strip section will extend under the body of the next adjacent strip section and vice versa, so that there occurs an interlocking relation between each of the strips 8 at each corner of the box which maintains the mitered edges in perfect alinement.

The strips 8 are moreover perforated, so that the tie rods 4 are adapted to project therethrough and the perforations 14, as well as the perforations 6 in the tongues, are countersunk, whereby, when the tie rods are headed over, the resulting heads will occupy the countersunk space thus provided to bring such heads substantially flush with the lower edge of the box, as shown in Figure 9. As a result of this construction, all four lower edges of the box are covered and concealed 20 throughout their entire lengths by the strips 8, mitered at the corners with flush joints to present a substantially plane surface at the lower edge of the box and the entire construction is held together by means of the tie rods 4. If desired, the ends of all of the slats may be recessed to receive the corner angles 3 in order to give flush outer walls at the four corners of the box, but I do not consider this necessary. However, when the corner angles are placed against the outer faces of the slats, they project the thickness of the metal and consequently the flanges 10 of the armor strips 8 are flared outwardly at the corners as indicated at 10a to provide for the increased dimension at these points.

Ordinarily the upper edges of the box do not require metal sheathing throughout, although the box of this invention may be made with both its upper and lower edges equipped with strips 8 in the manner described. For the purpose of illustration, however, the upper edges are merely shown as provided at their corners with corner caps 15, set in flush with the upper edges of the box and with the inner and outer walls and the tie rods 4 extend through perforations in said corner caps and are headed over in countersunk 40 perforations to provide a flush upper edge.

In this way, the upper edges of the box at the corners are provided with appropriate wear plates, while the entire lower edge of the box is covered 50 by the sheathing strips 8 which effectually serve the purpose of wear plates and protect the lower edge not only from wear, but from splitting, splintering and the like, the whole construction being held together by the tie rods 4, as stated. The strips 8 have been described as substantially U-shaped with flat bodies 9 and right angularly disposed flanges 10, although the cross section of these strips or wear plates may be modified or varied without departing from this invention.

The interior of the box construction is best shown in Figures 1, 2 and 3. The box is provided across its bottom with parallel pairs of supporting wires 15, which extend through the bottom end bars and near the lower edges thereof and are headed over as indicated at 16 in countersunk holes, so as to provide a flush exterior to the box. These wires which run longitudinally of the box are relatively heavy, but nevertheless require support intermediate their ends in order to properly carry the weight of the bottles supported thereon. Consequently, I provide a transverse brace 17 of novel and unique construction as shown. This brace is metallic and is in the form of a strap. It is made relatively wide and set on edge as 70 75

shown and near its upper edge is provided at its opposite ends with ears 18 preferably bent in opposite directions and secured by rivets 19 to the bottom slat of the box. Each opposite bottom slat is moreover rabbetted out to provide a shoulder 20 and the ears rest upon these shoulders which form abutments. The supporting wires 15 pass through perforations in and near the lower edge of the brace 17 and the weight 5 of these bottles is transferred to the brace and is in turn carried by the abutments 20, so as to take the strain off the rivets. As a matter of fact, the rivets 19 merely serve to hold the brace in position. The actual weight is carried by the abutments 20.

The box is provided with upper partition wires 21 which extend longitudinally and transversely of the box across the interior thereof and divide the upper portion thereof into compartments to receive the bottles individually. Lower partition wires also extend longitudinally of the box, as indicated at 22, and pass through perforations in the brace 17. Lower transverse partition wires 23 are also provided in a box which has but a single brace 17, but are not required in proximity to the brace because the brace extends sufficiently high to serve in itself as a partition wire and in a twelve compartment box if three braces 17 are employed spaced respectively below the three 25 upper transverse partition wires 21, no lower partition wires will be required as the braces will serve this function. In other words, the braces serve several functions; namely, they support the supporting wires 15; they act as stays for the longitudinal lower partition wires 22, and they serve the purpose of the lower transverse partition wires 23. In this way, a very strong construction results and all of the wires are braced as described. Furthermore, where a plurality of 30 such braces are used to take the place of the lower transverse wires, the necessity of independent wires of this character is eliminated.

To serve the purposes stated, the brace must be sufficiently deep to function primarily as a lower partition wire and in practice a sufficient depth is required to preclude the curved lower edge of the bottle from slipping thereover. The lower edges of milk bottles are generally curved on an arc of approximately one-half inch, so that, in practice, the braces 17 are preferably made to extend at least $\frac{3}{4}$ above the supporting wires 15, although I preferably make them extend an inch above. A greater dimension may be availed of, but is unnecessary. The upper 45 edges of the braces 17 are preferably rounded over, so as not to chip the bottles and in order to guide them to a proper seat on the supporting wires 15. The interior box construction which I have described is highly economical, as well as 50 thoroughly efficient for the performance of its intended functions. It brings about a degree of support and rigidity not heretofore found in boxes of this kind.

The foregoing detailed description sets forth 55 the invention in its preferred practical form and the invention is to be understood as fully commensurate with the appended claims.

Having thus fully described the invention, what I claim as new and desire to secure by Letters Patent is:

1. A box of the character described comprising side and end walls provided at their lower edges and adjacent the four corners of the box with recesses, a corner angle at each of the four corners of the box enclosing and concealing the

joints between side and end walls and provided at its upper and lower edges with tongues overlying the upper and lower edges of the box with the tongues at the lower edge housed in the recesses therein to bring the exposed faces of the 5 tongues flush with the lower edges of the box, wear strips in facial engagement with each of the lower edges of the box to cover and protect the same against wear, with the wear strips at the sides and ends of the box interfitting respectively 10 with one another at the four corners of the box to form flush joints, and means for securing said strips and corner angles to the walls of the box.

2. A box of the character described comprising side and end walls provided at their lower edges 15 and adjacent the four corners of the box with recesses, a corner angle at each of the four corners of the box enclosing and concealing the joints between side and end walls and provided at its upper and lower edges with tongues overlying the upper and lower edges of the box with the tongues at the lower edge housed in the recesses 20 therein to bring the exposed faces of the tongues flush with the lower edges of the box, wear strips in facial engagement with each of the lower edges 25 of the box to cover and protect the same against wear, with the wear strips at the sides and ends of the box interfitting respectively with one another at the four corners of the box to form flush joints, and tie rods extending through the 30 walls of the box, through the tongues of the corner angles and through the wear strips to secure all of said parts together.

3. A box of the character described comprising side and end walls provided at their lower edges 35 and adjacent the four corners of the box with recesses, a corner angle at each of the four corners of the box enclosing and concealing the joints between side and end walls and provided at its upper and lower edges with tongues overlying the upper and lower edges of the box with the tongues at the lower edge housed in the recesses therein to bring the exposed faces of the 40 tongues flush with the lower edges of the box, wear strips in facial engagement with each of the lower edges of the box to cover and protect the same against wear, with the strips at the sides and ends of the box interfitting respectively with one another at the four corners of the box to form flush joints, and tie rods extending through the 45 walls of the box, through the tongues of the corner angles and through the wear strips to secure all of said parts together, two of said tie rods being positioned adjacent each corner of the box and spaced from such corner.

4. A box of the character described comprising side and end walls abutting at their ends to form the body of the box, a corner angle at each of the four corners of the box overlying the corner of the box and overlapping the upper and lower edges thereof, wear strips armoring the lower edges of the four walls of the box with the strips of the side and end walls mitered with respect to one another at the four corners of the box and extending for the full length and width of the 60 box, and tie rods extending vertically through the walls of the box and through the wear strips and the corner angles to secure the parts together.

5. A box of the character described comprising side and end walls abutting at their ends to 70 form the body of the box, a corner angle at each of the four corners of the box overlying the corner of the box and overlapping the upper and lower edges thereof, wear strips armoring the lower edges of the four walls of the box with the strips 75

of the side and end walls mitered with respect to one another at the four corners of the box and extending for the full length and width of the box, the mitered ends of said strips being provided with offset projecting wings staggered with respect to one another whereby the wings of each strip are adapted to extend back of the body of the juxtaposed strips to cause interfitting of said strips for the purpose of maintaining the exposed surfaces of said strips in flush relation, and means for securing the strips and corner angles to the walls of the box.

6. A box of the character described comprising four walls arranged in rectangular relation 15 and at least the bottom edge of each of which four walls is enclosed within a channeled wear strip adapted to embrace the lower edges of said walls, said strips extending for the full length and width of the box and mitered at their corners 20 for flush abutting relation, the mitered end of each strip being provided with an offset tongue projecting under the body of the juxtaposed strip to maintain the exposed faces of the strip in the vicinity of the miter in flush relation with respect to one another, and means for securing said strips to the walls of the box.

7. A box of the character described comprising side and end walls arranged in rectangular relation to form the body of the box, wear strips secured to each of the four walls of the box and in face abutting relation to the lower edges of said walls, said wear strips extending uninterruptedly for the full length and width of the box with their portions which are in face abutting relation to the lower edges of the walls mitered at the corners of the box to provide collectively a four sided mitered frame extending uninterruptedly about the lower edge of the box, each of said wear strips being substantially U-shaped 40 in cross section to completely house the lower marginal edge portions of all four walls of the box.

8. A box of the character described comprising side and end walls, each composed of superimposed slats abutting at their corners to form a rectangular box body, a corner angle at each of the four corners of the box provided at its top and bottom with tongues overlying the upper and lower edges of the walls of the box and recessed into the bottom edges of said walls to produce a flush lower edge, wear strips of substantially U-shaped cross section extending for the full length and width of the box and overlying the bottom marginal portions of the four bottom slats and the corresponding portions of the corner angles and tongues, said strips being mitered at their ends and having offset projecting wings extending across the mitered joints and housed in concealed position between the strips and the tongues of the corner angles, and tie rods extending through the strips, tongues and the several slats in succession to secure the parts together, said strips being countersunk to receive the ends of the tie rods.

9. A box of the character described comprising side and end walls secured to one another to form a rectangular box body, supporting wires extending longitudinally of the box body and near the bottom thereof to support bottles resting thereon, and a brace extending transversely 65 across the box and near the bottom thereof and perforated for the passage of the supporting wires at right angles therethrough, said brace being provided at its opposite ends with perforated attaching lugs and the opposite walls of the box being provided interiorly with horizontal

abutments on which said lugs are adapted to seat, and means for attaching said lugs to the opposite walls of the box with the lugs seated on said abutments.

10. A box of the character described comprising side and end walls arranged in rectangular relation to form the body of the box, wear strips secured to each of the four walls of the box and in face abutting relation to the lower edges of said walls, said wear strips extending uninterruptedly for the full length and width of the box and mitered at the corners of the box to provide collectively a four sided mitered frame extending uninterruptedly about the lower edge of the box and the contiguous ends of adjacent wear strips having interlocking relation directly with each other.

11. A milk delivery box comprising side and end walls abutting at their ends to form the body of the box, a corner angle at each of the four corners of the box overlying the corner of the box and overlapping the upper and lower edges thereof, wear strips covering the lower edges of the four walls of the box and underlying and concealing the lower ends of the corner angles with contiguous ends of the strips of the side and end walls directly interfitting with respect to one another at the four corners of the box, and extending for the full length and width of the box, and means for securing the wear strips to the walls of the box.

12. A milk bottle box comprising side and end walls forming a rectangular box body, a plurality of supporting rods extending longitudinally of the box and near the bottom thereof to support the weight of bottles imposed thereon, correspondingly positioned upper and lower compartment rods extending longitudinally and transversely across the interior of the box above the supporting rods to divide said interior into compartments for individual bottles, there being incorporated in said box, in lieu of one of the lower transverse compartment rods which is omitted, a unitary girder of greater height than the distance between the lower compartment rods and the supporting rods, said girder extending transversely across the interior of the box and being perforated for the passage of the longitudinal supporting rods and the longitudinal lower compartment rods at right angles therethrough, and the opposite ends of said girder being individually rigidly anchored to the opposite walls of the box independently of any and all transverse rods.

13. In a milk delivery box having side and end walls with supporting rods extending longitudinally of the box and near its bottom to support the weight of bottles resting thereon and having correspondingly positioned upper and lower compartment rods extending longitudinally and transversely across the interior of the box above the supporting rods, a relatively thin, deep, unitary girder incorporated in lieu of one of the lower transverse compartment rods which is omitted, said girder being of greater depth than the distance between the other lower compartment rods and supporting rods and perforated for the passage of the longitudinal supporting rods and the lower longitudinal rods at right angles therethrough, and being sufficiently long to extend transversely across the interior of the box, and means for securing each end of the girder to one wall of the box independently of the means which secures the other end of the girder to the opposite wall of

the box, and both of said means being independent of any and all transverse rods.

14. A milk delivery box comprising side and end walls forming a rectangular box body, a plurality of supporting rods extending longitudinally of the box and near the bottom thereof to support the weight of bottles imposed thereon, correspondingly positioned upper and lower compartment rods extending longitudinally and transversely across the interior of the box above the supporting rods to divide said interior into compartments for individual bottles, there being incorporated in said box, in lieu of one of the lower transverse compartment
- rods which is omitted, a unitary girder of greater height than the distance between the lower compartment rods and the supporting rods, said girder extending transversely across the interior of the box and being perforated for the passage of the longitudinal supporting rods and the longitudinal lower compartment rods at right angles therethrough, and the opposite ends of said girder being provided with attaching ears at the upper portion of the girder, which attaching ears are riveted to the side walls of the box with individual rivets. 5 10

JOHN A. HOPWOOD.
